COMBINED WRIST WATCH CASE AND
A WATCH BAND

Paul G. Nolin, Cohoes, N. Y.

Application February 13, 1953, Serial No. 23,603

Term of patent 3½ years

(Cl. D45—4)

To all whom it may concern:

Be it known that I, Paul G. Nolin, a citizen of the United States, residing at Cohoes, in the county of Albany and State of New York, have invented a new, original, and ornamental Design for a Combined Wrist Watch Case and a Watch Band, of which the following is a specification, reference being had to the accompanying drawing, forming a part hereof.

Figure 1 is a perspective view of a combined wrist watch case and a watch band, showing my new design;

Figure 2 is a side elevational view thereof with the watch band in a slightly different position; and

Figure 3 is a top plan view thereof as shown in Figure 2.

The dominant feature of my design resides in the portions shown in full lines.

I claim:

The ornamental design for a combined wrist watch case and a watch band, as shown and described.

PAUL G. NOLIN.
